(57) **CLAIM**

The ornamental design for a folding reacher grabber tool, as shown and described.

DESCRIPTION

FIG. 1 is a first perspective view of a folding reacher grabber tool showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is a perspective view of another state of the folding reacher grabber tool thereof;

FIG. 10 is an enlarged view of the selected portion in FIG. 1; and,

FIG. 11 is an enlarged view of the selected portion in FIG. 1.

The broken lines shown in the drawings depict portions of the folding reacher grabber tool in which the design is embodied that form no part of the claimed design. The dot-dash broken lines depict enlarged portions that form no part of the claimed design.

1 Claim, 11 Drawing Sheets
